UNITED STATES PATENT OFFICE.

NAPOLEON DU BRUL, OF CINCINNATI, OHIO.

ROD-CUTTING DEVICE.

1,226,066.

Specification of Letters Patent.

Patented May 15, 1917.

Application filed September 18, 1915. Serial No. 51,454.

To all whom it may concern:

Be it known that I, NAPOLEON DU BRUL, a citizen of the United States, residing at Cincinnati, in the county of Hamilton and State of Ohio, have invented certain new and useful Improvements in Rod-Cutting Devices, of which the following is a specification.

This invention relates to cutting devices in which an object or material manufactured in continuous form or in long lengths, has to be subdivided to produce individual articles, and particularly to that class of such devices in which the object to be subdivided is fed constantly past a cutting point at which the line of feed is intersected by a cutter.

Some of the essential requisites of a successful cutting device of the kind referred to, are that the cutting stroke shall be made at rapidly recurring uniform intervals; that cutting shall take place without interrupting the feed of the object from which the article is being cut, thus necessitating movement of the cutter with the object during intersection of the line of feed; and that the cutting takes place without injuring the object, which is in some cases of delicate structure, for which purpose the cutting stroke is accompanied by rapid edge movement of the cutter itself.

In cutting devices of the class referred to, a high momentum must be rapidly overcome in reversing the direction of movement in fast running machines. Therefore, it is necessary that the construction of such a device shall be durable, cheaply maintained, as well as effective and satisfactory in operation.

One object of my invention is to produce a cutter capable of rapid action with a minimum of wear and noise, and simple and light in construction.

A further object is to produce a cutter that will be particularly valuable in rapidly severing objects of relative delicacy, such for instance as cigarettes, where a quick incision of the delicate cigarette rod is absolutely necessary in connection with an accurately timed cut to coincide with the continuous and rapid feed of the rod, these requirements increasing in importance with the capacity of the machine.

Another object of my invention is to provide a device of the character referred to, that can be easily applied as a unit to ma-

chines already in the market and to replace worn out or inferior cutting devices now in such service.

Another object of my invention is to provide a device of the kind referred to that will require the minimum of attention from the operator for lubrication.

A further object is to provide a device that may be conveniently assembled in exact relation and one in which access to the several parts is easily obtained for repairs or adjustment, and one providing easily changeable parts for cutting objects of different lengths.

A further object is to reduce to a minimum the number and weight of reciprocating parts, so that greater speeds or a greater number of cuts per minute can be obtained.

With the above and other objects in view, my invention consists in the construction of the different parts and also in their combination and arrangement in relation one to another as set forth particularly in the drawings and description hereto attached.

An illustrative embodiment of the invention designed for use on a cigarette machine is shown in the accompanying drawings, in which like characters represent similar parts, and in which—

Figure 1 is a top plan view;

Fig. 2 is an end elevation;

Fig. 3 is a front elevation;

Fig. 4 is an end elevation at the cutter end;

Fig. 5 is a detail view of the cutter and its mounting;

Fig. 6 is a detail view of the arcuate block by means of which the lever-stud engages in the slot of the disk-cam.

In the drawings is shown a machine frame 1, having a drive shaft 1^a on which is a driving gear 1^b, meshing with an intermediate gear 1^c. A housing 2 is mounted on the frame 1, provided with bearings 2^a, carrying shaft 3, at one end of which is mounted a gear 3^a, deriving movement through gears 1^c and 1^b from the main shaft 1^a. Gear 1^c is supported by the arm K which is allowed to swing on shaft 1^a and held in place on the housing projection and permitted to be moved in a slotted projection to admit change gears 3^a of different sizes. Other positive driving means may also be employed at this point without departing from my invention.

The housing 2 may be inclosed to form

an oil chamber 2^b in which is revolved a cam 3^b, mounted on shaft 3. The housing also carries a horizontal slide bearing on which is mounted a slide member 4, adapted to slide longitudinally in the housing 2, and held in place by the caps 2^c, and having part of its inner surface exposed to the oil chamber. The slide member 4 carries two rollers 4^a through means of the studs 4^b, fitted transversely in the slide member and fixed therein by set screws 4^c, each having one end reduced to receive a roller, and having at its other end an adjusting nut 4^d by which to adjust the stud. The surfaces of the rollers being conical, longitudinal adjustment of the studs causes them to fit accurately to the working faces of the cam 3^b. The cam 3^b has its edges operating between the two rollers 4^a, which reciprocates the slide member 4 and the cutter longitudinally of the path of the rod to be severed.

On one side of the housing next to slide 4, an opening 4^{ax} is made to facilitate the insertion and withdrawal of the studs 4^b, with the rollers thereon, from the outside of the housing, and to adjust the rollers to the cam. The opening 4^{ax} may be closed by a plate screwed on the outside face to prevent the oil from splashing out at this point. When in operation, a cover 2^d can be applied to the top of the oil chamber to prevent the oil from splashing out. By this construction, the cam and the slide member are inclosed in a receptacle where oil is put to lubricate the several elements, such as between the edges of the cam and the rollers, the bearing of the rollers upon the reduced ends of the studs, the reciprocating slide member 4, and the bearings of the cam shaft.

The reciprocating slide 4 is provided with any convenient means of mounting the cutter 5, as for instance a shaft 5^a, which I show projecting through the slide 4, having on one end adjusting nuts 5^b for taking up wear, and upon the other end arms 6 and 5^c, which act as a single arm on said pivot shaft, but are relatively adjustable about the axis of the shaft to insure complete intersection of the line of feed by the edge of the circular knife 5 mounted on said arm 5^c.

The arm 5^c carries on one end the bearing 5^d, in which is journaled the shaft 5^e, which carries the aforesaid knife 5, said knife being held in place thereon between two collars 5^f, by clamp nut 5^g. At the other end of the knife shaft is mounted a pulley 5^h, around which is run a belt for rotating the knife 5, said belt being led from any suitable source of rotary motion, and being guided in any convenient way to permit freedom of oscillation of the knife mounting without impairing drive of the belt.

To provide for the above-mentioned relative angular adjustments of the arms 6 and 5^c, arm 6 has an extension 6^a provided with

a slot 6^b and is held to arm 5^c by a bolt 6^c. By thus providing means of adjusting the knife 5 with relation to the path of travel of the object to be cut, I provide for the wearing down of the knife by repeated sharpening, to a small diameter.

To the reciprocating slide member 4 is secured a projecting bracket 7, carrying cutting ledges 7^a to support the rod during the cutting stroke. This construction is not only simple and durable, but extremely efficient for this purpose.

With the above-described construction and relation of parts, the slide 4 can be of light weight, and reciprocation is required of only a few, comparatively light parts.

A further advantage of this construction and arrangement is that the knife can come squarely down on the top of the rod to be severed. As the seam of a cigarette rod is formed on the top, when cutting oval-shaped cigarettes especially, it is desirable to cut squarely down on the seam and pass through the smaller dimension of the elliptical oval shape of the rod, if the best possible results are to be attained.

To produce the up-and-down movements of the knife, the arm 6 has a rearward extension 6^d, having a bearing 6^e, in which is journaled a stud 6^f, held in place by suitable means as by limiting nut 6^g, the other end of which forms an arcuate block 6^h shown by Fig. 6, working in the slot 3^c on the face of an eccentrically disposed disk-cam 3^d. While this construction is preferred, any other suitable means to this end may be employed without departing from my invention. The face of the eccentric cam is approximately the curve of the cam 3^d, as shown in Figs. 1 and 3, to permit the block 6^h to follow without disengagement at one end of the throw or interference at the other end. The block 6^h being held in engagement with the cam 3^d, the lever arm 6^d is moved up and down vertically, thus causing the cutter 5 to pass into and out of the path of the article to be cut.

Eccentric cam 3^d is so timed with the cam 3^b that the cut takes place while the cutter is traveling in the direction and at the same speed of the article to be cut and at the time desired.

Experience has demonstrated that this construction makes a cutting device of a very smooth-running character and one that is not subject to shocks either in the longitudinal or vertical movement and is, therefore, capable of operation at relatively high speed.

With the construction as hereinbefore described, wear can be taken up at points where it mostly occurs, and all parts are readily accessible for this purpose, or for replacing when necessary.

To sum up the operation, as the main

shaft revolves, power is transmitted to the cam shaft of the cutting device. Cam 3^b working between the rollers 4^a causes the slide 4 to reciprocate longitudinally, according to the amount of throw given by cam 3^b. At the predetermined point, the cutter is dipped down and up through the rod by eccentric 3^a, and while the cutting proceeds, the slide 4 travels with the rod so as to avoid buckling. At a further point in the stroke, the cutter 5 is lifted clear of the path of the article to be cut, and by the movement of cam 3^b is returned to its first position.

I claim:—

15 1. In a rod cutter, a housing having a lubricant chamber, a slide mounted on said housing and intersecting the lubricant chamber, a shaft also intersecting said chamber, a cam located within the chamber and coacting with the slide to reciprocate the same, a knife mounted upon the slide outside of the chamber, and means for developing a transverse reciprocating movement in the knife comprising a second cam mounted on the cam shaft; said slide having mounted thereon, studs within the chamber, in position to receive the first-mentioned cam in developing the said reciprocating movement.

20 2. In a rod cutter, a housing having a lubricant chamber, a slide mounted on said housing and intersecting the lubricant chamber, a shaft also intersecting said chamber, a cam located within the chamber and coacting with the slide to reciprocate the same, a knife mounted upon the slide outside of the chamber, and means for developing a transverse reciprocating movement in the knife comprising a second cam mounted on the cam shaft; said slide having mounted thereon, studs within the chamber, in position to receive the first-mentioned cam in developing the said reciprocating movement; said studs being introduced transversely through the slide and being accessible from the outer side of said slide.

25 3. In a rod cutter, a housing having a lubricant chamber, a slide mounted on said housing and intersecting the lubricant chamber, a shaft also intersecting said chamber, a cam located within the chamber and coacting with the slide to reciprocate the same, a knife mounted upon the slide outside of the chamber, and means for developing a transverse reciprocating movement in the knife comprising a second cam mounted on the cam shaft; said slide having mounted thereon, studs within the chamber, in position to receive the first-mentioned cam in developing the said reciprocating movement; said 30 studs being introduced transversely through the slide and being accessible from the outer side of said slide; said lubricant chamber having an opening permitting the introduc-

tion and withdrawal of said studs without removal of the slide.

4. In a rod cutter, the combination of a housing having a lubricant chamber, a slide mounted upon said housing and intersecting said chamber, a cam located in said chamber and coacting with said slide to reciprocate the same, a knife mounted on said slide and reciprocating therewith in the line of rod feed, and means for developing a transverse reciprocating movement in the knife; the mounting for said knife comprising a rocker-arm pivotally supported on the slide and carrying a bearing in which the knife is mounted to rotate; and the means for developing said transverse reciprocating movement comprising a second arm extending from the knife mounting, and a second cam mounted upon the shaft of the cam within the lubricant chamber; said second cam having a face groove substantially corresponding in curvature with the curvature of the slide reciprocating cam, and said second arm carrying a stud having its end working in said face groove.

5. In a rod cutter, the combination of a housing having a lubricant chamber, a slide mounted upon said housing and intersecting said chamber, a cam located in said chamber and coacting with said slide to reciprocate the same, a knife mounted on said slide and reciprocating therewith in the line of rod feed, and means for developing a transverse reciprocating movement in the knife; the mounting for said knife comprising a rocker-arm pivotally supported on the slide and carrying a bearing in which the knife is mounted to rotate; and the means for developing said transverse reciprocating movement comprising a second arm extending from the knife mounting, and a second cam mounted upon the shaft of the cam within the lubricant chamber; said second cam having a face groove substantially corresponding in curvature with the curvature of the slide reciprocating cam, and said second arm carrying a stud having its end constructed in the form of a curved segment fitted to and working in said face groove.

6. In a rod cutter, a housing constructed with a receptacle, a cam mounted to operate within the receptacle, a sliding member having rollers projecting into the receptacle, and taking reciprocating movement from the cam, and a cutter reciprocating with the sliding member; said housing having an outside opening next to the sliding member to permit the rollers to be applied to or withdrawn from the sliding member.

The foregoing specification signed at Washington, District of Columbia, this 17th day of September, 1915.

NAPOLEON DU BRUL.
